UNITED STATES PATENT OFFICE.

ISAAC HIRSCH, OF CHICAGO, ILLINOIS.

CARVING-FORK.

SPECIFICATION forming part of Letters Patent No. 659,397, dated October 9, 1900.

Application filed May 11, 1900. Serial No. 16,257. (No model.)

To all whom it may concern:

Be it known that I, ISAAC HIRSCH, a citizen of the United States, residing at Chicago, in the county of Cook and State of Illinois, have 5 invented a new and useful Improvement in Carving-Forks, of which the following is a specification.

My invention relates to improvements in carving-forks of the class provided with 10 spring-controlled bifurcated guards pivoted to opposite sides of the shanks of the forks; and my object is to provide improved spring-controlling mechanism for the guard of a particularly simple, durable, inexpensive, and 15 efficient construction.

In the drawings, Figure 1 shows a fork provided with my improvement; Fig. 2, an enlarged section taken on line 2 of Fig. 1; Fig. 20 3, an enlarged broken perspective view of the guard; and Fig. 4, a perspective and partly-broken sectional view of a plug-piece enlarged, which forms the guard-holding pivots and cooperates with the prongs of the guard to form the spring-controlling mechanism therefor.

The fork A may be of the usual construction, formed with a handle *a*, shank *b*, and prongs *c*. Fitting closely an opening *d* through the shank *b* and held rigidly therein is a plug-30 piece B, preferably of suitably-hardened steel or the like. The plug-piece is formed at one end with a pointed conical projection *e* and at its opposite end with an elongated or knife-blade projection *f*. The body of the plug-piece may be entirely within the opening *d* and the projections *e* *f* extend beyond opposite sides of the shank of the fork. The guard C is of stiff springy metal, having the usual stem portion *x* and the usual prongs *y* *y*. 35 The guard is provided at the inner side of one of its prongs *y* with an indentation *g* just large enough to suitably engage the pointed projection *e*, and at the inner side of its other prong it is provided with straight 40 sockets *h* *i*, which cross each other at a desired angle. The walls *h* *i* of the sockets are abrupt and form stops or shoulders, while the opposite walls and intervening spaces are cut away to form at one or each side of the 45 cross a convex cam or cam-surface *k*, highest 50

at the center. The guard is placed in position by expanding its prongs *y* with a suitable expanding-tool and passing them over the shank *b* until the socket or indentation *g* engages the pivot *e* and one of the sockets *h* 55 or *i* engages the knife-blade projection *f*. The natural stiffness of the guard-prongs holds them in engagement with the pivots *e* *f* without danger of displacement. When the projection *f* engages the socket *h*, the guard 60 is in the closed or folded position shown in Fig. 1. To open the guard, it is pressed at its prongs *y* in the downward direction to swing it on the pivots *e* *f* and raise the guard or stem portion *x*. In this movement the 65 cams *k* slide over the projection *f* against the resistance against expansion of the spring-prongs *y* until the socket *i* nears the projection *f*, when the shoulder *i'* will be sprung or snapped against the projection *f*, which will 70 then engage the socket *i*. The guard is closed by swinging it in the opposite direction against the resistance of the spring-prongs until the shoulder or stop *h'* snaps against the projection *f*. The cam-surfaces *k* and 75 knife-blade projection *f* are sufficiently hard to resist wear, so that the construction, while being particularly effective, is very durable, and as it dispenses with the springs and spring-catches usually provided it is simple 80 and inexpensive to construct.

While I prefer to construct my improvements as shown and described, they may be variously modified as to details of construction without departing from the spirit of my 85 invention as defined by the claims. Of course the bearing projections may be upon the guard-prongs and the bearing-sockets on the fork-shank, if such reversal of construction is preferred, and, furthermore, the cam 90 construction may be at both sides of the shank instead of at one side only.

What I claim as new, and desire to secure by Letters Patent, is—

1. In a fork, the combination with the 95 shank thereof, of a plug extending rigidly through the shank and provided at opposite ends with pivot-bearings, a bifurcated guard provided with spring-prongs pivotally connected with said bearings, and a cam at the 100

pivot at one side of the shank operating to expand the prongs in the movement of the guard between its opened and closed positions, substantially as and for the purpose set forth.

2. In a fork, the combination with the shank thereof, of a rigid plug passing through the shank provided at opposite ends with the pointed bearing projection *e* and knife-blade bearing projection *f*, a bifurcated guard having spring-prongs, with a socket *g* in one

prong to engage the bearing *e*, and crossed sockets *h i*, in the other prong to engage the bearing *f*, having the shoulders *h' i'*, and intermediate cams *k*, all constructed and arranged to operate substantially as and for the purpose set forth. 15

ISAAC HIRSCH.
